[57] CLAIM

The ornamental design for a spout, as shown and described.

DESCRIPTION

FIG. 1 is a top plan view of a spout embodying our new design;

FIG. 2 is a right side elevational view thereof, the left side elevational view being a mirror image of the right side elevational view;

FIG. 3 is a bottom plan view thereof;

FIG. 4 is a rear elevational view thereof;

FIG. 5 is a front elevational view thereof;

FIG. 6 is a perspective view thereof;

FIG. 7 is a top plan view of a second embodiment of a spout;

FIG. 8 is a right side elevational view of the spout of FIG. 7, the left side elevational view being a mirror image of the right side elevational view;

FIG. 9 is a bottom plan view of the spout of FIG. 7;

FIG. 10 is a rear elevational view of the spout of FIG. 7;

FIG. 11 is a front elevational view of the spout of FIG. 7; and,

FIG. 12 is a perspective view of the spout of FIG. 7.
